BOWLING GAME TABLE

John D. Vogel and John K. Miles, both $\frac{1}{2}$ Arvin
Industries, Inc., Columbus, Ind. 43201

Filed Feb. 20, 1969, Ser. No. 15,849

Term of patent 14 years

Int. Cl. D21—01

U.S. Cl. D34—5

Fig. 1

Fig. 2

Fig. 3

Fig. 4

FIG. 1 is a top plan view of a bowling game table showing our new design;

FIG. 2 is a side elevation thereof;

FIG. 3 is a front elevation thereof; and

FIG. 4 is a rear elevation thereof.

We claim:

The ornamental design for a bowling game table, as shown.
